ROTARY PUMP

Edwin E. Smith, Santa Clara, Calif., assignor to Fluid Dynamics Corp., Santa Clara, Calif., a corporation of California

Filed Jan. 24, 1962, Ser. No. 168,407

14 Claims. (Cl. 103—131)

This invention relates to a rotary pump and more particularly to a rotary pump of the type having two pumping chambers.

At the present time, there is a need for a pump in the food processing fields and other fields which can be utilized for pumping large quantities of product efficiently and without contamination. There is also a need for such a pump which can be readily disassembled for cleaning.

In general, it is an object of the present invention to provide a rotary pump which particularly lends itself to pumping liquid and semi-liquid food products.

Another object of the invention is to provide a rotary pump of the above character which particularly lends itself to the pumping of heavy or thick liquids such as molasses or chocolate.

Another object of the invention is to provide a rotary pump of the above character in which the pumping chambers and the piston are cantilevered on one end of the pump to facilitate disassembly and assembly of the pump.

Another object of the invention is to provide a rotary pump of the above character which can be readily disassembled for cleaning.

Another object of the invention is to provide a rotary pump of the above character in which there is substantially less wear than in conventional pumps.

Another object of the invention is to provide a rotary pump of the above character which creates an unusually high vacuum.

Another object of the invention is to provide a rotary pump of the above character in which the action of the piston is such that it minimizes viscous shearing and has a lesser tendency to homogenize materials.

Another object of the invention is to provide a rotary pump of the above character in which the pumping chambers are sealed from any lubrication provided for the pump as, for example, in the bearings.

Additional objects and features of the invention will appear from the following description in which the preferred embodiment is set forth in detail in conjunction with the accompanying drawings.

Referring to the drawings:

FIGURE 1 is a front elevational view of a pump incorporating my invention.

FIGURE 2 is a cross-sectional view taken along the line 2—2 of FIGURE 1.

In general, my rotary pump consists of a housing in which a shaft is rotatably mounted in the housing. A flanged shaft is eccentrically journaled in the first named shaft and has its longitudinal axis parallel to the longitudinal axis of the first named shaft but spaced from the longitudinal axis of the first named shaft. A timing plate is affixed to the housing and means is provided forming a connection between the flanged shaft and the timing plate so that circular gyrating movement of the flanged shaft occurs without axial rotation as the first named shaft is rotated. A casing is mounted on the housing and is provided with inlet and outlet openings. The casing is also provided with concentric cylinder walls which define a working space. Partition means is provided in the working space and serves to separate the inlet opening from the outlet opening in the casing. A piston is affixed to the flanged shaft and moves therewith. The piston is provided with a cylinder which operates in the working space. The cylinder is formed with a slot to permit cir-

2

cular gyratory movement of the piston about the partition means.

As shown in the drawings, my rotary pump consists of a shaft housing 11 which has mounted thereon two feet 12 and 13 which serve as a base for the pump. The shaft housing 11 is substantially bell-shaped as shown in FIGURE 2. A bell-shaped shaft 14 is rotatably mounted within the housing 11 by a pair of roller bearings 16 and 17. The bearing 16 is located at the input end of the housing 11, whereas the bearing 17 is located in the output end of the housing. The bearing 16 is mounted in an adjusting nut 18 which is threaded into the power input end of the housing. This adjusting nut is provided with tool receiving recesses 19 so that the nut can be adjusted longitudinally of the housing 11 to obtain the proper clearance between the piston and the pump casing as herein-after described. It is then locked in position by a bolt 25 extending through ears 20 provided on the shaft housing 11. The ball bearing 16 is held in place on the bell-shaped shaft 14 by a lock nut 21 which is threaded onto the bell-shaped shaft as shown and a lock washer 22 disposed between the lock nut and the bearing 16. The bearing 17 is mounted in the housing 11 in a suitable manner such as by a press fit. An O-ring 23 is disposed between the adjusting nut 18 and the housing 11 to form an oil-tight seal between the adjusting nut and the housing. A seal 15 is provided in the adjusting nut 18 to prevent oil leakage from around the shaft 14.

A flanged shaft 26 is eccentrically mounted or mounted off center in the bell shaft 14 so that when the bell shaft 14 is rotated, an eccentric gyrating motion is supplied to the shaft 26. To accommodate the flanged shaft 26, the bell shaft 14 is provided with a cylindrical recess 27 which has a diameter which is substantially greater than the diameter of the flanged shaft. The inner end of the flanged shaft is carried by a ball bearing 28 mounted within the bell shaft 14. The ball bearing 28 is held in position relative to the bell shaft 14 by a set screw 29 threaded into the bell shaft 14. The shaft 26 is held in the ball bearing 28 by a snap ring 30 seated in a groove 31 in the shaft 26. Access to the set screw 29 is provided by a plug 35 threaded into the housing 11. An intermediate portion of the flanged shaft 26 is carried by a roller bearing 32. The roller bearing 32 is held in place by a snap ring 33 seated in a groove 34 provided in the flanged shaft 26.

It will be noted that the bell shaft 14 is formed in such a manner that it is balanced with the flanged shaft 26 mounted therein which, as hereinabove described, includes the piston 54. It is for this reason that the upper portion of the bell shaft, as viewed in FIGURE 2, is of substantially greater thickness than the lower portion. The lower portion is also provided with an opening 36 to further decrease the weight of the lower portion to thereby provide a counterweight in the shaft 14 for the shaft 26 which is eccentrically mounted within the shaft 14.

Means is provided for preventing axial rotation of the flanged shaft 26 during the gyrating motion of the shaft 26 and consists of a timing plate 38 which is affixed to the housing 11 by suitable means such as cap screws 39. The timing plate 38, as shown in FIGURE 2, lies immediately behind the flanged portion 26a of the flanged shaft 26 and lies in a plane parallel thereto. The plate 38 is coupled to the flanged portion of the flanged shaft 26 by suitable means such as by pins 41 which are mounted in the flanged portion 26a of the flanged shaft 26 and which have rollers 42 rotatably mounted thereon and held in position by snap rings 43 seated in grooves 44 provided in the pins 41. The rollers 43 are disposed in circular openings 46 provided in the timing plate and travel in the circular openings in a manner disclosed in my copending application Serial No. 53,970, filed Sept. 6, 1960, issued

as Patent No. 3,125,032 to thereby permit eccentric or gyroscopic motion of the flanged shaft, while at the same time preventing axial rotation of the flanged shaft.

Although the flanged shaft 26 is shown as a unitary structure, it is readily apparent that, if desired, the flanged portion could be a separate member which could be secured to a separate shaft.

A casing 45 is mounted on the housing 11 in a suitable manner such as by the use of studs 50 which are threaded into the housing and hex nuts 55 which are threaded onto the studs. The casing is provided with inlet and outlet openings 46 and 47 and concentric outer and inner walls 48 and 49 which define an annular working space 51 therebetween. Partition means in the form of a removable divider 52 is mounted in grooves 53 in the walls 48 and 49 and in the working space 51 between the concentric cylinder walls and serves to separate the inlet openings 46 from the outlet openings 47 of the pump. It should be appreciated that the inlet and outlet openings 46 and 47 can either serve as inlet or outlet openings depending upon the direction of rotation of a piston 54 mounted in the casing of the pump.

The piston 54 is affixed to flanged shaft 26 in a suitable manner such as by means of a hex nut 56 which is threaded onto a threaded extension 26b provided on the flanged shaft 26 and engaging a collar 58 which engages the piston. The piston 54 is provided with a cylindrical portion 54a which operates in the working space 51 as shown particularly in FIGURE 2 of the drawings. Although not shown in the drawings, additional means can be provided for affixing the piston 54 to the flanged shaft so that the piston will not rotate with respect to the flanged shaft under load. For example, one of the pins 41 could be formed so that it extends through the flanged portion 26a of the flanged shaft and so that it extends into a recess in the piston.

The piston 54 is provided with an end plate portion 54b which has a diameter which is substantially greater than the outer diameter of the cylindrical portion 54a of the piston and the inner diameter of the cylindrical wall 48 of the casing 41 so that the working space or pumping chamber 51 can be sealed off from the remainder of the pump.

The cylindrical portion 54a of the piston can be formed entirely of metal if desired. However, in certain applications, we have found it desirable to cover the cylindrical portion 54a of the piston with bonnet 61 of a suitable resilient material such as rubber. The bonnet 61 is secured to the metal cylindrical portion 54a in a suitable manner such as by molding or bonding.

I have found the use of the rubber bonnet 61 to be particularly advantageous when the pump is utilized for pumping food products because the rubber bonnet presents a smooth surface to which the food product does not cling. In addition, the rubber bonnet makes it possible to eliminate the use of any seals between the piston and the casing and still achieve excellent pumping action in which there is little hydraulic slippage and a high vacuum is maintained. However, it has been found that the pump will still operate satisfactorily without the use of such a resilient bonnet provided on the cylindrical portion 54a. However, if the bonnet is not used, the external diameter of the cylindrical portion 54a must be increased to take up the space which is taken up by the bonnet 61.

Sealing means is provided for sealing the pumping chamber or working space 51 from the shaft and bearing chamber 62 in the housing 11. The sealing means consists of a compression seal 63 which is mounted in recesses in the outer end of the outer concentric cylinder wall 48 of the casing 41 and a compression seal 64 which is mounted in the outer end of the cylindrical wall 49 of the casing 41. These compression seals 63 and 64 can take any suitable form. However, I have found it desirable to utilize an annular member 66 of a suitable material such as a metal filled plastic having a planar an-

nular face yieldably urged into engagement with the end plate portion 54b of the piston by a pair of O-rings 67 mounted behind the annular sealing member 66. I have found it desirable to utilize two O-rings rather than one or a double O-ring for this purpose because the two O-rings or the double O-ring urge substantially all portions of the annular member 66 into engagement with the plate-like portion of the piston. If only a single O-ring were utilized, the flat annular member 66 would have a tendency to become convex and, therefore, would not form as good a seal. I have found it desirable to utilize plastic for the sealing member 66 because if a small impurity should by chance scratch the surface of the sealing member 66, the plastic would have a tendency to flow back to its original condition to provide a planar surface to again establish an excellent seal between the sealing member and the piston 54.

In order to minimize the wear between the outer extremity of the plate-like portion 54b of the piston and the casing 41, I have found it desirable to provide an annular thrust washer or wear ring 68 which is loosely mounted in an annular recess 69 in casing 41 so that its outer planar surface is engaged by the plate-like portion 54b of the piston. This wear ring 68 can be formed of any suitable material such as bronze or brass. If the pump is utilized for pumping materials which have acid in them which may cause an electrolytic action to set in on the wear ring material, a metal-filled plastic or other suitable material can be used.

In order to extend the life of this wear ring 68, I have provided an oiler 70 of conventional construction which is mounted on the housing 11 as shown and which applies a suitable oil such as white mineral oil through a passage 71 into contact with the wear ring 68. It is desirable to utilize mineral oil in certain applications of the pump because if a small portion of the mineral oil should pass through the seal 63, the mineral oil will not spoil the product which is being pumped by the pump. However, any other lubricant compatible with the product being pumped, such as water, may be used.

It should be pointed out that the wear ring can be eliminated in many instances and that it is only desirable to provide such a wear ring when the pump is manufactured of materials which are particularly subject to galling or fretting, as, for example, when the pump is manufactured from stainless steel. If the pump is manufactured from cast iron, bronzes and the like, a wear ring should be unnecessary.

Sealing means is provided in the housing 11 to prevent oil in the chamber 62 in the housing 11 from coming in contact with the food being pumped in the pumping chamber. It consists of an annular seal ring 74 mounted in an annular recess 76 provided in the rear portion of the flanged portion 26a of the flanged shaft 26. This seal can be of any suitable type such as a rubber "Quad-ring" manufactured by the Minnesota Rubber Co. of Minneapolis, Minnesota. As can be seen from FIGURE 2 of the drawings, this Quad-ring engages the smooth face of the timing plate 38 to provide a seal between the timing plate 38 and the flanged portion 26b to thereby isolate the pumping chamber 51 from the oil-filled chamber 62 in the housing 11 in which the bearings and shafts 14 and 26 are mounted.

As will be noted from FIGURE 2, the housing 11 can be filled through the plug 35 and can be drained through the drain plug 78. The bearings within the housing are lubricated by the splash of oil created as the enlarged portion of the bell shaft 14 moves into and out of the oil within the housing.

An annular chamber 81 is provided beyond the outer extremity of the flanged portion 26a of the shaft 26 to collect material in the event there is some flow of material through the seals 74 and the seals 63 and 64. A drain (not shown) is provided for draining this chamber. Thus, by chance if some oil from the housing 11 should

flow past the seal 74, the oil can be drained from the chamber before it builds up sufficient pressure so that it can pass into the pumping chamber 51. Also, if some of the product being pumped should pass the seal 63, it also can be drained from the chamber before it passes into the housing 11.

To provide additional assurance that there will be no cross-flow of material from the chamber 62 in the housing 11 to the pumping chamber 51 or vice versa, I have provided an annular diaphragm 82 which is formed of a suitable material such as rubber. The outer margin of the diaphragm is secured to the housing 11 in a suitable manner such as by a snap ring 83. The inner margin of the diaphragm 82 is beaded as shown and is seated in a recess 86 in the flanged portion 26a of the shaft 26. From this construction, it can be seen that the diaphragm 82 provides an additional seal between the pumping chamber 51 and the chamber 62 within the housing 11.

Operation of my rotary pump may now be briefly described as follows. Let it be assumed that the pump is in the position shown in dotted lines in FIGURE 1. As is shown therein, the working space 51 is divided into an outer pumping chamber A which is formed between the piston and the outer cylindrical wall 48 and an inner pumping chamber B which is formed between the piston and the inner wall 49. Also, let it be assumed that the shaft 14 is being rotated in a counterclockwise direction as viewed in FIGURE 1. In the position shown, the outer chamber A is discharging out the outlet opening 47. At the same time, the inner chamber B is completing its intake. Continued oscillation or gyratory movement of the piston 54 causes the outer chamber to continue its discharge, the intake end of the inner chamber to be sealed and the outer chamber to begin its intake. Continued oscillation causes the outer chamber to complete its intake and the inner chamber to begin discharging. Further oscillatory or gyratory movement of the piston 54 causes the outer chamber to be sealed, the inner chamber to continue its discharge and also to commence its next intake. Thereafter, the outer chamber begins its discharge and the inner chamber continues its intake to return to the positions shown in FIGURE 1 after which the same sequence of operations take place. This operation is described in detail in my copending application Serial No. 53,970, filed September 6, 1960, issued as Patent No. 3,125,032.

Although the basic mode of operation of my pump is substantially conventional, my pump has many advantages. For example, it should be noted that the casing 41 and the piston 54 are cantilevered on one end of the shaft and bearing housing 11. This facilitates easy removal of the casing and piston. For example, the casing can be removed merely by removing the nuts 43. This exposes the working space 51 provided between the concentric cylinder walls 48 and 49 and also exposes the piston 54 so that all the surfaces which come in contact with the product being pumped can be readily cleaned without difficulty.

From this construction, it can be seen that the pump particularly lends itself to food processing applications in which frequent cleaning and repair are required.

The pump also lends itself to food processing applications and other applications in which the product being pumped must be completely isolated from the remainder of the pump. As can be seen, a multiplicity of seals have been provided to ensure that there will be no intermixing of the product from the pumping chamber 51 and the oil in the oil chamber 62 provided within the housing 11. This has a distinct advantage in that the oil in the oil chamber will not become contaminated and also that the product being pumped will not be contaminated with oil. The construction is such that even if there should be a small quantity of material pass through the seals, it is collected on the outside of the chamber 81

by the diaphragm 82 and can be readily drained off and washed out by removal of the casing 41 and the piston 54.

As explained, the rubber-covered piston disclosed in the pump also provides numerous advantages. In addition to being particularly adapted for many food processing applications because of the fact that it presents a smooth surface to which food does not cling, it also maintains a high vacuum without the use of complicated seals. Also, the rubber facing or bonnet provided on the piston permits greater latitude in manufacturing tolerances. Also, it has been found to give lesser pulsations in the fluid being pumped because of the compressibility of the rubber bonnet. The rubber-covered piston also decreases hydraulic slip or, in other words, my pump has less hydraulic slip at a given pressure and given capacity than conventional pumps. For example, in one embodiment of my pump, I found that the pump could pump 48 gallons at no pressure and could still pump 44 gallons per minute at 100 pounds pressure. This indicated that the hydraulic slip was only 4 gallons per minute at 100 pounds pressure.

As also described previously, although my pump has been disclosed as being provided with a rubber bonnet, other types of materials can be utilized for the cylindrical piston. For example, the piston could be faced with a plastic material such as nylon or Teflon, or it could be coated with a ceramic or faced with a very hard facing material and still operate satisfactorily. With such hard surfaces, it is possible to pump liquids containing materials which are very hard.

My rotary pump also has other advantages. For example, the gentle rolling action of the piston within the smooth bore of the pumping chamber minimizes viscous shearing and exhibits far less tendency to homogenize materials than conventional pumps. It is for this reason that my rotary pump can handle materials having a relatively low viscosity up to viscosities of one million SSU without changing internal clearances in the pump. Also, due to the gyratory or rocking motion of the piston, nails and other foreign matter can usually pass through the pump without damaging the pump.

From the foregoing description, it can be seen that my rotary pump is a piston type rotary displacement pump in which the piston gyrates instead of rotating. The pumping chamber is completely isolated from all the parts of the pump. As explained above, two separate pumping chambers A and B are formed by the oscillating piston. In operation, the rotating point of contact between the piston and the concentric cylinder walls of the casing serves both to push fluid out (discharge pressure) and to pull fluid in (intake vacuum). The two pumping chambers are phased 180° apart to provide continuous positive displacement.

It is apparent from the foregoing that I have provided a new and improved rotary pump which has a particularly unique construction which lends itself to simple disassembly for cleaning and maintenance. Also, the construction of my pump is such that it lends itself to applications in which the pumping chamber must be completely isolated from the remainder of the pump.

I claim:

1. In a rotary pump, a housing, a first shaft rotatably mounted in said housing, a second shaft eccentrically journaled in said first shaft, a timing plate affixed to the housing, means forming a connection between the second shaft and the timing plate to prevent rotation of the second shaft but permitting circular gyratory movement of the second shaft as the first shaft is rotated, a separate casing removably mounted on said housing and having inlet and outlet openings, said casing also having inner and outer concentric cylinder walls defining a working space, partition means carried by the casing in the working space separating the inlet opening from the outlet opening, and a piston affixed to said second shaft and movable therewith, said piston having a radially extending

flange engaging the outer concentric wall of the casing, the piston having a cylinder operating in said working space to provide two pumping chambers in the working space, said piston having a slot straddling said partition means for permitting circular gyratory movement of the piston about the partition means.

2. A rotary pump as in claim 1 wherein said housing is formed with a base and wherein said casing and said piston are cantilevered on said housing so that they extend outwardly and away from said housing.

3. A rotary pump as in claim 1 wherein said cylinder has inner and outer concentric walls together with a covering of resilient material bonded to said inner and outer walls of the cylinder for movement therewith, said resilient covering engaging the concentric inner and outer cylinder walls of the casing and being free of engagement with said partition means.

4. A rotary pump as in claim 1 together with an integral bonnet of resilient material bonded to said cylinder for movement therewith and engaging the inner and outer concentric walls of the casing, said bonnet being free of engagement with said partition means.

5. A rotary pump as in claim 1 together with a wear ring mounted in said casing and wherein the flange of the piston continuously engages the wear ring during its gyratory motion.

6. A rotary pump as in claim 5 together with means for applying a lubricant to the wear ring.

7. A rotary pump as in claim 1 together with sealing means mounted between the casing and the piston, said sealing means including an annular member having a planar surface engaging the piston, and means comprising a pair of O-rings disposed on the other side of the annular member and yieldably urging the annular member into engagement with the piston.

8. A rotary pump as in claim 7 together with additional sealing means disposed between the flange and the timing plate.

9. A rotary pump as in claim 1 together with an annular diaphragm of pliable material and means for affixing the outer margin of the annular diaphragm to the housing and the inner margin of the diaphragm to the flange.

10. In a rotary pump, a bell-shaped housing, a bell-shaped shaft rotatably mounted in said housing, a second shaft journalled in said bell-shaped shaft and having its longitudinal axis parallel to the longitudinal axis of the bell-shaped shaft but spaced from the longitudinal axis of the bell-shaped shaft, means connected to the second shaft for preventing axial rotation of the second shaft but permitting circular gyratory motion of the second shaft, a separate removable casing mounted on said housing and

having inlet and outlet openings, said casing extending outwardly of the housing and having concentric inner and outer cylinder walls defining a working space, partition means in the working space separating the inlet opening from the outlet opening, and a piston affixed to said second named shaft and movable therewith, the piston having a cylindrical portion with inner and outer concentric walls operating in said working space and dividing said working space into outer and inner pumping chambers, said cylindrical portion having a slot straddling said partition means to permit circular gyratory movement of the piston about the partition means.

11. A rotary pump as in claim 10 wherein said bell-shaped shaft is counter-balanced to compensate for the off-center mounting of the second named shaft.

12. A rotary pump as in claim 10 together with sealing means for isolating the pumping chambers from the housing.

13. A rotary pump as in claim 10 together with a bonnet of resilient material covering and being bonded to the inner and outer concentric walls of the cylindrical portion of the piston said bonnet being free of engagement with the partition means.

14. A rotary pump as in claim 10 wherein the piston is formed with a radially extending end plate having a diameter substantially greater than the diameter of the outer cylindrical wall portion of the casing together with a wear plate mounted in said casing and engaged by said end plate as the piston operates.
